UNITED STATES PATENT OFFICE

MORRIS F. HAMZA, OF UNION CITY, NEW JERSEY

MACHINE FOR COVERING TASSEL MOLDS

Application filed May 1, 1929. Serial No. 359,537.

This invention relates to a machine for covering tassel molds and has for its primary object to provide, in a manner as hereinafter set forth, a machine of such class by means of which a layer of silk or the like may be evenly distributed over the entire surface of a mold, thereby replacing the old hand method called lashing on tassels.

A further object of the invention is to provide a machine for the purpose aforesaid including as a part thereof, means for reciprocating and rotating a mold to be covered, with respect to a needle reciprocating in a fixed longitudinal plane.

With the foregoing and other objects in view, the invention consists of the novel construction, combination and arrangement of parts as hereinafter more particularly described, and as illustrated in the accompanying drawings wherein is shown an embodiment of the invention; but it is to be understood that such description and drawings are to be taken as illustrative and that the invention is intended to be limited only by the scope of the claims hereunto appended.

In the accompanying drawings in which like numerals are employed to designate like parts throughout the same:

Figure 1 is an elevation of a machine in accordance with this invention.

Figure 2 is a top plan thereof.

Figure 3 is a sectional plan taken at a point indicated by the line 3-3 in Figure 1.

Figure 4 is an enlarged fragmentary plan.

Figure 5 is a section taken on line 5-5 of Figure 4.

Figure 6 is a section taken on line 6-6 of Figure 4.

Figure 7 is a section taken on line 7-7 of Figure 4.

Figure 8 is a diagrammatic view showing the needle supporting and actuating means in elevation.

Figure 9 is a sectional detail view showing the return movement of the needle from the inside of a mold.

Figure 10 is a view similar to Figure 9 showing the return movement of the needle from the outside of a mold.

Figure 11 is a vertical section of a mold

after the same has been removed from the machine.

Referring to the drawings in detail, the numeral 1 indicates a base plate from which a plurality of uprights 2 project for supporting a frame 3. Mounted on the base 1 is a swivel 4 which is provided with an actuating handle 5 and upon which is mounted a motor 6. Mounted within the frame 3 and having its ends extending through the ends of the frame is a crank shaft 7, upon the forward end of which is mounted a drive pulley 8. Carried by the shaft of the motor is a friction pulley 9 which may be brought into engagement with the pulley 8 to drive the latter by manipulation of the handle 5. The crank shaft 7 is provided with a crank 10 which is connected by means of an arm 11 with a similar crank 12 formed on a shaft 13 which is supported below the base plate 1. Secured to the rearward end of the shaft 13 is a flier 14 which encircles a stationary bobbin 15. The flier 14 is formed with a beveled face 16 and the bobbin 15 is provided with an upstanding thread guide 17.

Fixedly mounted on the crank 7 is a gear 18 which is in mesh with a similar gear 19, fixedly mounted on a shaft 20 supported within the frame 3. Fixedly mounted on the shaft 20 is a beveled pinion 21 which is in mesh with a beveled gear 22 on a vertically disposed worm shaft 23. The gears 21 and 22 have a two to one ratio in order that the worm shaft 23 may be driven at one-half the speed of the shafts 7 and 20. The worm shaft 23 is provided with a worm 24 which is in mesh with a gear 25 mounted on a shaft 26 which is journaled in a bracket 27 suspended from the frame 3.

The lower end of the worm shaft 23 is journaled in the base plate 1 and adjacent the lower end thereof, the worm shaft is provided with a cam 28 which is mounted within a pair of jaws 29 secured by means of a bracket 30 to a lever 31. The lever 31 extends longitudinally of the base plate 1 and is pivotally connected, as indicated at 32, to a bar 33 which extends longitudinally of the base plate 1 and is fixedly secured thereto. The lever 31 and bar 33 project forwardly beyond the

forward end of the machine as indicated in Figure 1. The rearward end of the lever 31 is pivotally connected by means of a link 34 with a carriage indicated generally by the numeral 35.

5 The carriage 35 consists of a lower plate 36 and an upper plate 37 which are rigidly connected together by means of a plurality of posts 38. The lower plate 36 is substantially rectangular in form and is provided at its forward edge with a boss 39 which is slidably mounted on a rod 40 supported by means of a pair of legs 41 in spaced relation to the base plate 1. Adjacent the rearward edge 10 thereof the lower plate 36 rests on a rib 42 which is secured to the base plate 1. The plate 36 is formed with a plurality of elongated slots 43, 44 and 45 which extend radially with respect to the vertical axis of the plate. The plate is provided with a similar slot 46 which extends across the vertical axis of the plate and which is in longitudinal alignment with the slot 43.

15 The upper plate 37 is of annular construction and is provided in its outer peripheral edge with a recess 48. Fixedly secured to the plate 37, by means of a clamp 49, is a hollow arm 50 within which one end of a bar 51 extends in telescoping relation. A set screw 52 20 extends through the clamp 49 and upper wall of the arm 50 into engagement with the bar 51 to provide for the adjustment of the bar longitudinally of the arm. The projecting end of the bar 51 is provided with a bearing 53 through which extends a vertical shaft 54, the lower end of which projects through the slot 43 in the lower plate 36. Fixedly mounted on the shaft 54, in spaced relation to the lower end thereof, is a friction roller 55, the periphery of which is adapted to engage the periphery of a mold 56 when the latter is positioned on the lower plate 36.

25 Above the bearing 53 the shaft 54 is provided with a pair of spaced sprockets 57 and 58. Secured to the upper plate 37, in spaced relation to the hollow arm 50, is a hollow arm 59 which is maintained in position by means of a clamp 60. Extending into the arm 59 in telescoping relation is a bar 61, the projecting end of which is provided with a bearing 62 through which a shaft 63 extends. The lower end of the shaft 63 projects into the slot 44 in the lower plate 36 and spaced from the lower end of the shaft 63, the latter 30 is provided with a friction roller 64, the lower edge of which rests on the upper face of the plate 36 and the peripheral edge of which is adapted to engage the peripheral edge of the mold 56. The roller 64 is normally maintained in engagement with the mold 56 by means of a spring 65 disposed within the hollow arm 59 and the respective ends of which abut the bar 61 and a bar 66 positioned within the arm 59 in spaced relation to the bar 61.

35 Pivottally mounted to a bracket 67 carried

by the arm 59 is a latching member 68 which is provided with a nose 69 overlapping the outer end of the arm 59 to prevent the bar 66 from being forced out of the arm 59 by the action of the spring 65.

40 Secured to the upper plate 37, in spaced relation to the arms 50 and 59, is a hollow arm 70 which is maintained in position by means of a clamp 71. Extending into the arm 70 in telescoping relation is a bar 72 which may be adjusted longitudinally of the arm 70 by means of a set screw 73 extending through the clamp 71 and upper wall of the arm 70. The projecting end of the bar 72 is provided with a bearing 74 through which a vertical shaft 75 extends. The lower end of the shaft 75 projects into the slot 45 in the lower plate 36 and spaced from the lower end thereof, the shaft 75 is provided with a friction roller 76 for engagement with the mold 56. Above the bearing 74, the shaft 75 is provided with a sprocket 77. A similar sprocket 78 is provided on the shaft 63, above the bearing 62.

45 Longitudinally adjustable of the arm 50 is a clamp 79 which provides a bearing for a vertical shaft 80. Fixedly mounted on the shaft 80 is a sprocket 81 which is connected by means of a chain 82 with a sprocket 83 on the shaft 26 supported by the bracket 27. Mounted on the shaft 80, in spaced relation to the sprocket 81, is a sprocket 84 which is connected by means of a chain 85 with the sprocket 58 on the vertical shaft 54. Engaging the sprockets 57, 77 and 78 is an endless chain 86 which passes over a friction pulley 87 disposed within the recess 48 in the outer peripheral edge of the upper plate 37. The pulley 87 is mounted on one end of a bell crank 88 which is pivotally connected as indicated at 89 to the upper plate 37 of the carriage. The opposite end of the bell crank 88 is connected to the hollow arm 70 by means of a spring 90, the tension of which actuates the bell crank and pulley 87 to prevent slack in the chain 86.

50 Secured to the base 1 is a bracket 91 which is provided with a vertically disposed friction roller 92 for engagement with the forward face of the hollow arm 50 to prevent any strain from being imparted to the latter by the chain 82.

55 Secured to the rearward end of the frame 3 is a bracket 93 through which a needle holder 94 slidably extends. Carried by the bracket 93 is a guide member 95 which is provided with a finger 96 having a bearing 97 through which the needle holder 94 slidably extends. The needle holder 94 is provided with a fixed collar 98 to which one end of a link 99 is pivotally connected, the opposite end of the link 99 being pivotally connected to a boss 100 projecting rearwardly from a disc 101 fixedly secured to the rearward end of the crank shaft 7. The boss 100 is eccentrically disposed with respect to the disc 101 and the link 100

99 is of slightly greater length than the radius of the disc 101. Adjustably secured to the lower end of the needle holder 94 is a needle 102 which carries a thread 103 which passes upwardly through a guide 104 extending rearwardly from the guide member 95.

Extending upwardly from the frame 3 is a supporting member 105 which is provided with a resilient keeper 106 through which the thread 103 extends. In the embodiment shown the thread 103 is formed of four individual strands indicated at 107, each of which is unwound from a spool 108 rotatably supported on an extension 109 for one of the upright members 2. Projecting from the supporting member 105 is a tension element 110 which is adapted to hold a block of paraffin or the like indicated at 111. When it is desired to apply paraffin to the strands 107 of the thread, the element 110 is positioned in a manner to provide for the passage of the strands over the paraffin as the strands travel from the spools 108 to the keeper 106.

In the operation of my machine, the lever 5 is actuated to bring the pulleys 9 and 8 into engagement by means of which the crank shaft 7 is driven by the motor 6. Due to the cranks 10 and 12 and crank arm 11, the shaft 13 is driven simultaneously with the shaft 7 whereby the flier 14 is rotated about the bobbin 15. The disc 101 is rotated with the crank shaft 7, thereby reciprocating the needle holder 94 due to the link 99 which pivotally connects the needle holder 94 with the disc 101, eccentrically of the latter.

Due to the meshing gears 18 and 19, the shaft 20 is rotated simultaneously with the crank shaft 7 and the motion of the shaft 20 is imparted to the worm shaft 23 through the medium of the bevelled gears 21 and 22. The rotation of the worm shaft 23 causes the cam 28 thereon to reciprocate the lever 31 and due to the link 34 which pivotally connects the lever 31 with the carriage 35, the reciprocation of the lever 31 is imparted to the carriage 35 upon which the mold 56 is seated. The gearing ratio provides for a complete reciprocative movement of the needle 102 while the carriage 35 is completing one-half of its reciprocating movement. In this manner alternating complete reciprocating movements of the needle will be on the outside of the mold and the intermediate movements of the needle will be on the inside of the mold. During its movements the needle coacts with the bobbin in the usual manner to form a loop 112.

During the operation of the machine a slow rotary movement is imparted to the mold 56 due to the frictional contact therewith of the rollers 55, 64 and 76 which are actuated by the chains 86, 85 and 82, the latter of which is driven by the sprocket 83 on the shaft 26 which is actuated by means of

the gear 25 meshing with the worm 24 on the worm shaft 23.

When it is desired to change the mold, the bell crank 88 is actuated against the tension of the spring 90 to slack the chain 86, and the compression of the spring 65 is released by removing the nose 69 from the end of the bar 66. The roller 64 may then be withdrawn from the mold 56 and the latter readily removed from the machine. Due to the slots 43, 44 and 45 in the lower plate 36 and the adjusting screws 52 and 73 for the bars 51 and 72, the machine may be used in covering molds of various sizes.

It is thought that the many advantages of a machine in accordance with this invention will be readily apparent, and although the preferred embodiment of the invention is as illustrated and described, it is to be understood that various changes in the size, shape and arrangement of parts may be resorted to, so long as such changes fall within the scope of the invention as defined in the appended claims.

What I claim is:

1. A device of the character described comprising, a base, a carriage slidably mounted thereon for supporting a mold to be covered, a reciprocating needle for coaction with a bobbin mechanism, a plurality of rollers supported by the carriage in frictional engagement with the mold, means for rotating said rollers, and means for reciprocating said carriage, said last named means including a shaft adapted to be rotated by a prime mover, an eccentric fixedly mounted on said shaft, a pair of jaws between which said eccentric is disposed, a pivoted lever with which said jaws are rigidly connected, and a link having its respective ends pivotally connected to said lever and carriage.

2. A device of the character described comprising, a base, a carriage slidably mounted thereon for supporting a mold to be covered, a needle for coaction with a bobbin mechanism, a plurality of rollers supported by the carriage in frictional engagement with the mold, shafts upon which the rollers are fixedly mounted, sprockets fixedly mounted on the shafts, an endless chain extending around the sprockets, means operatively connecting one of said shafts with a prime mover to provide for the rotation of such shaft, and means for reciprocating said needle and carriage whereby the latter is moved in one direction of its reciprocating movement simultaneously with the movement of the needle in both directions of its reciprocating movement.

3. A device of the character described comprising, a base, a carriage slidably mounted thereon for supporting a mold to be covered, a reciprocating needle for coaction with a bobbin mechanism, means for rotating the mold, and means for reciprocating said carriage to alternately position the mold on op-

posite sides of the path of travel of the needle, said last named means including a shaft adapted to be rotated by a prime mover, an eccentric fixedly mounted on said shaft, a pair of jaws between which said eccentric is disposed, a pivoted lever with which said jaws are rigidly connected, and a link having its respective ends pivotally connected to said lever and carriage.

4. A device of the character described comprising, a base, a carriage slidably mounted thereon for supporting a mold to be covered, a needle for coaction with a bobbin mechanism, a plurality of rollers carried by the carriage, shafts upon which the rollers are fixedly mounted, bars projecting radially from the vertical plane of the mold and having said shafts extending transversely and rotatably therethrough, one of said bars being slidable longitudinally, a tension element normally forcing said slidable bar toward the vertical plane of the mold, means for rotating the shafts to provide for the rotation of the mold, and means for reciprocating said needle and carriage whereby the latter is moved in one direction of its reciprocating movement simultaneously with the movement of the needle in both directions of its reciprocating movement.

5. A device of the character described comprising, a base, a carriage slidably mounted thereon for supporting a mold to be covered, said carriage having a series of slots disposed radially with respect to its vertical axis, a shaft extending into each slot, a roller on each shaft for frictional engagement with the mold, a reciprocating needle for coaction with a bobbin mechanism, means for reciprocating the carriage, and means for rotating said rollers.

6. A device of the character described comprising, a base, a carriage slidably mounted thereon for supporting a mold to be covered, said carriage having a series of slots disposed radially with respect to its vertical axis, a shaft extending into each slot, a roller on each shaft for frictional engagement with the mold, a reciprocating needle for coaction with a bobbin mechanism, means for reciprocating the carriage, and means for rotating said rollers, said last named means including a sprocket on each shaft, an endless chain passing over said sprockets, and a sprocket on one of said shafts for driving the latter.

7. A device of the character described comprising, a base, a carriage slidably mounted thereon for supporting a mold to be covered, a reciprocating needle for coaction with a bobbin mechanism, a plurality of rollers in frictional contact with the mold, shafts upon which the rollers are fixedly mounted, sprockets fixedly mounted on said shafts, an endless chain passing around said sprockets, means for driving the chains to impart rotary motion to the mold, a pulley having said chain

passing thereover, a pivoted bell crank mounting said pulley, tension means connected with the bell crank for actuating the same to prevent slack in said chain, and means for reciprocating said carriage.

In testimony whereof, I affix my signature hereto.
